DESIGN FOR A SOAP DISPENSER

William B. Petzold, Pittsfield, Mass., assignor to General Electric Company, a corporation of
New York

Application October 17, 1940, Serial No. 95,889

Term of patent 14 years

To all whom it may concern:

Be it known that I, William B. Petzold, a citizen of the United States, residing at Pittsfield, in the county of Berkshire, Commonwealth of Massachusetts, have invented a new, original, and ornamental Design for a Soap Dispenser, of which the following is a specification, reference being had to the accompanying drawing, forming a part thereof.

In said drawing:

front and one side of a soap dispenser, showing my new design.

I claim:

The ornamental design for a soap dispenser, as shown.

WILLIAM B. PETZOLD.
